UNITED STATES PATENT OFFICE.

JULIUS SCHÜLKE, OF BERLIN, GERMANY.

REGULATOR FOR COMPRESSED GAS.

SPECIFICATION forming part of Letters Patent No. 269,599, dated December 26, 1882.

Application filed June 30, 1882. (No model.) Patented in France May 3, 1882, No. 147,507; in Austria-Hungary May 10, 1882, No. 8,489; in Italy May 19, 1882, XVI, 14,201; in Belgium May 31, 1882, No. 57,905, and in Germany October 23, 1882.

To all whom it may concern:

Be it known that I, JULIUS SCHÜLKE, of Berlin, Prussia, have invented certain new and useful Improvements in Regulators for Compressed Gas, of which the following is a specification.

This invention has reference to an improved pressure-regulator for compressed illuminating-gas as used in railway-carriages, steamships, and other vehicles, by which the gas is supplied to the burners in a regular manner and at low pressure, without being affected by the motion of the car or vessel; and the invention consists of a gas-pressure-regulator which is provided with a diaphragm that is connected to the operating-lever mechanism of the regulating-valve, which mechanism is balanced by a fulcrumed lever and an adjustable counter-weight, so as to neutralize the effect of the vibratory motion of the car or vessel upon the valve. The regulating-valve is of spherical shape, its stem being applied to the fulcrumed and spring-pressed regulating-lever and tightly fitted to its valve-seat.

The invention consists, lastly, of the connection of the closed space above the diaphragm by a pipe with the hot-air space at the inside of one of the lamps supplied with gas from the pressure-regulator, so as to secure a uniform pressure in the space above the diaphragm and the upper part of the lamp.

In the accompanying drawings, Figure 1 represents a top view with parts broken off to show the interior construction of my improved pressure-regulator for compressed illuminating-gas; and Figs. 2 and 3 are vertical central sections taken at axial planes, respectively, on the lines *x x* and *y y*, Fig. 1, of the same.

Similar letters of reference indicate corresponding parts.

The compressed illuminating-gas which is carried along on railway-trains, steamboats, and other vehicles has to pass through a pressure-regulator, so as to be conducted at low pressure to the lamps. The pressure-regulators consist of a cylindrical casing with a metallic or other diaphragm, to the space at one side of which the gas is supplied through an induction-opening provided with a regulating-valve. In the closed position of the eduction-

opening the diaphragm is raised by the pressure of the gas entering from the gas-reservoir, and thereby the regulating-valve closed by the action of a spring-pressed-lever mechanism that is connected to the diaphragm and the valve, so that consequently the supply of gas is interrupted. In this position of the regulator there is a certain fixed pressure below the diaphragm, which pressure is determined by the tension of a regulating-spring. As soon as the eduction-opening of the regulating apparatus is opened the valve of the supply-opening is opened by the lowering of the diaphragm to such extent that as much gas is admitted through the induction-opening as is passed off through the eduction-opening. Whether a larger or smaller quantity is drawn off per unit of time, the pressure in the regulator below the diaphragm remains the same, owing to the action of the regulating mechanism. In the gas-regulators as heretofore used this uniformity of pressure could not be kept up, owing to the disturbing influence of the oscillating motion of the cars upon the movable parts of the regulating apparatus. Another objection is that the valves of the regulating devices heretofore used were soon worked out, so as not to fit closely and tightly, owing to the change of position and the weight of the regulating mechanism. To obviate these objections the weight of the regulating-lever mechanism is balanced by means of a lever and counter-weight, and a valve of spherical shape employed, as will appear by reference to the drawings, in which—

A represents the cylindrical casing of my improved pressure-regulator, which is provided with a covering-lid A', that is firmly secured thereto by fastening-screws S. The cylindrical body or casing A of the regulator is provided with an induction-opening, B, that is connected to the supply-pipe leading from the reservoir to the regulator by a screw-coupling, B', having an interior valve-seat, b. A diaphragm, C, of sheet metal, is arranged at the interior of the casing A, and secured tightly into position to its seat *a* by a flange or rim, *a'*, of the lid A', and by an intermediate rubber ring or gasket, *a*². The larger space below the diaphragm C forms the regulating-

chamber through which the illuminating-gas has to pass before being distributed to the lamps.

A disk-shaped plate, d , of sheet metal, is secured to the top of the diaphragm C, so as to stiffen the same and serve for attaching the connecting-rod e , which extends downward from the center of the diaphragm, it being pivoted at its lower end to the regulating elbow-lever D, and above the pivotal connection with the same to a second fulcrumed lever, E, that is provided at the outer end with a counter-weight, g^2 , Fig. 2.

The induction-opening is closed by a ball-valve, F, which fits tightly upon the seat b , the ball-valve being applied to the end of a forked stem, F' , which is pivoted to the upwardly-bent end of the elbow-lever D. The elbow-lever D is fulcrumed to a fixed bracket-arm, g , at the apex of its angle, and acted upon by a spiral spring, D' , that is attached at its upper end to the elbow-lever D, and at its lower end by a clamp-screw, h , to a cylindrical extension, h' , in the bottom of the casing A. The gas enters the regulator through the induction-opening B of the valve F, and passes out through the eduction-opening to the burners. The course of the gas is indicated by arrows in Fig. 2.

Between the induction-opening and the ball-valve F is interposed a number of perforated screens, b' , for retaining any coarse impurities carried along by the gas.

The fixed stem F' of the regulating-valve F is pivoted to the shorter arm of the elbow-lever D, and the weight of the valve F, valve-stem F' , and elbow-lever D balanced by a lever, E, that is fulcrumed to a support, g' , and provided with an adjustable counter-weight, g^2 . The counter-weight is so adjusted on the lever E that it counterbalances the weight of the regulating-valve F and its lever mechanism, neutralizes the injurious effect of the vibratory motions of the car upon the regulating-valve, and insures consequently the more reliable working of the regulator. Owing to the spherical shape of the valve F and the pivotal connection of its stem with the elbow-lever D, the valve F will always close tightly onto its seat b whenever it is pressed thereon, so as to shut off the supply of gas. A more reliably working valve is thus obtained, which will close the inlet-opening in any position of the regulating-lever, and even after being worn by long use.

A tube, G, is connected to the top of the regulating apparatus and forms the communication between the smaller space above the diaphragm, with the heated air filling the upper space in one of the lamps supplied by the regulator. This connection of the space of the regulator above the diaphragm with the hot-air space of a lamp serves for the purpose of preventing the sudden extinction of the lamps, which is caused by means of strong air-currents, and the difference of pressure which is exerted by them upon the diaphragm and up-

on the air supplied to the lamp. In other words, if the connecting-tube G be not used, the lamps arranged in the top of railway-cars and at the head of the locomotive are exposed to strong air-pressure, which differ frequently from the pressure to which the regulators that are generally arranged below the bottom of the car are exposed. Consequently the lamp and the diaphragm of the regulator are acted upon by air-pressure differing in strength. It is obvious that these differences affect the regular working of the regulator—as, for instance, if the regulator is set for a certain pressure and a greater pressure would be exerted upon the diaphragm the result would be that no gas would be supplied to the burner, and that the light would be extinguished or at least be very irregular. These differences in pressure take place most frequently when the cars enter or leave tunnels, depots, &c., and are the cause of the sudden extinction of the locomotive head-light and ear-lamps. If, however, in place of the usual air-openings in the top of the regulator, the upper space is connected by the tube G with a lamp or with the head-light of the locomotive, then the atmospheric air which surrounds the regulator cannot act upon the diaphragm, but the latter is acted upon by the heated air in the lamp. The tube G terminates preferably in the air-supply channel of the lamp, but may also terminate near the same, whereby the air-pressure at the upper part of the lamp would be transmitted by the connecting-tube to the diaphragm of the regulator, and thereby the required uniformity of pressure established and a sudden extinction of the lamps prevented.

Having thus described my invention, I claim as new and desire to secure by Letters Patent—

1. In an apparatus for regulating the pressure of compressed illuminating gas, a supply-pipe, a screw-coupling having an interior valve-seat, a screen between the seat and the induction opening, and a spherical regulating-valve fixed to a rigid stem and fitted to the valve-seat, substantially as described.

2. In an apparatus for regulating the pressure of compressed illuminating-gas, a supply-pipe, a screw-coupling having an interior valve-seat, a spherical regulating-valve, fulcrumed and weighted lever mechanism attached to said valve, a spiral spring acting on the lever D, a flexible diaphragm, and a pipe, G, combined with the air-supply channel of the lamp, substantially as described.

3. In a gas-pressure regulator, the combination of the valve, the valve-seat, the elbow-lever D, pivoted to the valve-stem F, the spiral spring D' , the connecting-rod e , the diaphragm C, the plate d , the fulcrumed lever E, and the counter-weight g^2 , substantially as described.

In testimony that I claim the foregoing as my invention I have signed my name in presence of two subscribing witnesses.
